William K. Najjar, 2875 Taft SW.,
Wyoming, Mich. 49509

Filed Mar. 22, 1974, Ser. No. 453,727

Term of patent 14 years

Int. Cl. D4—02

U.S. Cl. D4—18

FIG. 1.

FIG. 2.

FIG. 3.

FIG. 4.

FIG. 1 is a perspective view of a combined toothbrush and dental floss holder, showing my new design;

FIG. 2 is a side elevational view thereof;

FIG. 3 is a bottom view thereof;

FIG. 4 is a top plan view thereof.

The broken line disclosure of the dental floss in FIGS. 1-3 is for illustrative purposes only and forms no part of the claimed design.

I claim:

The ornamental design for a combined toothbrush and dental floss holder, substantially as shown and described.
